THEODORE P. GARANKIN
INVENTOR.

BY John P. Neronow

ATTORNEYS.

UNITED STATES PATENT OFFICE.

THEODORE P. GARANKIN, OF NEW YORK, N. Y.

RAILROAD TIE.

Application filed January 25, 1923. Serial No. 614,904.

To all whom it may concern:

Be it known that I, THEODORE P. GARANKIN, citizen of Russia, and resident of New York city, in the county of New York and State of New York, have invented certain new and useful Improvements in Railroad Ties, of which the following is a specification.

My invention relates to railroad ties and 10 has a particular reference to ties adapted to be locked to the ballast underneath.

The object of my invention is to provide a tie which could be moved for the purpose of aligning or readjusting the rails and 15 which could be securely fastened to the roadbed.

With the ordinary ties it is difficult to keep the rails from getting out of position under heavy strain, for instance, on the 20 curves. And when the ties are moved in order to correct the position of the rails, then this movement still further weakens the bond between the ties and the roadbed.

With my tie I provide a means to secure 25 the tie to the ballast underneath, also a means for moving the tie in relation to this securing means, locking the tie in each new position.

My invention is more fully described in 30 the accompanying specification and drawing in which—

Fig. 1 is a plan view of my tie with the rails attached, Fig. 2 is a side elevation of same. Figs. 3 and 4 represent a modification, Figs. 5 and 6 are also modifications, 35 Fig. 7 is a plan view of the spacing blocks as they would look in the assembled condition, Fig. 8 is an elevation of this block assembly, and Fig. 9 is a view of the adjusting device.

My tie 1, when made from a channel beam (Figs. 1 and 2), is provided with a tie plate 2 underneath. This tie plate has a downward extending tongue 3 imbedded in the 45 ballast 24 under the tie. The plate has a stud 4 passing through a slot 5 in the tie 1. A cover plate 19 with a central aperture is placed on the stud to cover the slot 5 and is fastened with a nut 6 and a lock nut 7. The 50 cover plate is guided in its place by projections or guiding pins 20. The space in the slot 5 on both sides of the stud is filled with spacing blocks 8, 9, 10, 11, 12, 13, 14, 15, 16, 17 and 18 of different dimensions. These 55 blocks can be removed by prying them out with a suitable lever through end slots 21.

Rails 22 are attached to the tie in a regular manner with rail plates 23.

The object of the tie plate 2 and the tongue 3 is to lock the tie to the roadbed right under the tie, where this roadbed is fully compressed by the weight of the passing trains. With this arrangement it is impossible for my tie to become accidentally displaced or to 60 slide endwise on the roadbed.

When it becomes necessary to move the tie for the purpose of realignment of the rails, then my tie can be moved in relation to the tongue 3 of the plate 2 without disturbing the position of the tongue itself in the compressed roadbed.

For this purpose the nuts 6 and 7 are loosened, and the cover plate 19 turned at right angle exposing the slot 5 with the spacing blocks 8—18. These blocks are then 75 removed, and a screw jack (Fig. 9) or a similar adjusting device is placed with a clevis 26 over the stud 4 or nuts 6 and 7, and with a slot 29 of a bracket 28 over pins or lugs 25 of the tie. The screw 35 is then 80 turned with a suitable wrench fitting over the square or hexagonal portion 27, until the tie moves to a desired position. The gravel or similar ballast is first removed from under the front end of the tie and replaced 85 again when the movement is completed.

The spacing blocks are then replaced in a new order so as to fill completely spaces on both sides of the stud 4. These blocks are made of various different lengths so that 90 their positions can be rearranged for any new position of the tie in relation to the tie plate with the stud 4.

The cover plate 19 is turned again to its proper position and is tightened in this position with the nuts 6 and 7. The tie will be just as firmly attached to the roadbed as before, since the position of the locking tongue 3 in the compressed ballast has not been changed.

Instead of one tongue 3 two or more may be employed. Fig. 4 shows an arrangement with two tongues 31. In this case a sliding box 30 is employed instead of the plate 2, this construction being especially suitable 105 for a solid tie, made from wood, for instance. The slot 5 may be made in a special plate 32 attached to the tie with screws 33 and provided with lugs 34 on the ends for the screw jack.

It should be noted that the lugs 25 may be omitted altogether if the screw jack is 110

provided with hooks adapted to be attached to the ends of the plate 32 or to the ends of the tie 1 itself.

Figs. 5 and 6 illustrate a modified arrangement in which the adjusting screw 35 is permanently located on the tie passing with its middle portion through a nut 36 of the tie plate 37 having tongues 38. The nut or threaded lug 36 is placed in a slot 42 with the spacing blocks 8-17. The ends of the screw 35 are provided with square heads 41 and are placed in bearing brackets 40 attached to the tie 1.

Important advantages of my tie are, that it can be permanently secured with its tie plate and tongue to the compressed ballast underneath, and, at the same time, can be easily realigned and moved in relation to this tie plate, also that it can be permanently locked in each new position.

I claim as my invention:

1. In a railroad tie, the combination with a tie, means to secure said tie to the road-bed, and means to move said tie in relation to said securing means.

2. In a railroad tie, the combination with a tie, means to secure said tie to the road-bed, means to move said tie in relation to said securing means, and means to lock said tie in each new position.

3. In a railroad tie, the combination with a tie, means to secure said tie to the ballast underneath, means to move said tie in relation to said securing means, and means to lock said tie with said securing means.

4. In a railroad tie, the combination with a tie, a sliding member on said tie, means to secure said sliding member to the ballast underneath, a screw operated device adapted to move said tie in relation to said sliding member, and means to lock said tie and said sliding member together.

5. In a railroad tie, the combination with a tie, a sliding member on said tie, a plurality of lugs on said sliding member, said lugs being adapted to be permanently imbedded in the ballast underneath said tie, means to move said tie in relation to said sliding member, and means to lock said tie with said sliding member.

6. In a railroad tie, the combination with

a tie, a sliding member on said tie, a plurality of lugs on said sliding member adapted to be imbedded in the ballast underneath said tie, a stud on said sliding member, a slot in said tie for said stud, a plurality of spacing blocks of various length filling said slot on both sides of said stud, a cover plate for said blocks, and tightening nuts on said stud.

7. In a railroad tie, the combination with a tie, a sliding plate on said tie, a plurality of tongues on said plate extending downward and adapted to be imbedded in the ballast under the tie, a stud on said plate, a slot in said tie for said stud, a plurality of spacing blocks on said slot filling the space on both sides of said stud, a cover for said blocks, nuts on said stud adapted to tighten together said tie and said plate, and means to move said tie in relation to said plate.

8. In a railroad tie, the combination with a tie, a sliding plate on said tie, means to secure said plate to the ballast under the tie, a stud on said plate, a slot in said tie for said stud, a plurality of spacing blocks of different length filling said slot on both sides of said stud, a cover for said blocks, a plurality of nuts on said stud adapted to tighten together said tie and said plate, and a screw operated device adapted to engage said stud and said tie for the purpose of moving said tie in relation to said stud.

9. In a railroad tie, the combination with a tie, a sliding plate on said tie, a plurality of tongues on said plate, said tongues being adapted to be imbedded in the ballast under said tie, a stud on said plate, a slot in said tie for said stud, a plurality of removable spacing blocks of different lengths filling the spaces on both sides of said stud in said slot, a cover plate for said slot with said blocks, nuts on said stud adapted to draw together said tie with said sliding plate, and a screw operated device for moving said tie in relation to said plate, said device being adapted to engage with one end said stud and with the other end said tie.

Signed at New York in the county of New York and State of New York this 22nd day of January A. D. 1923.

THEODORE P. GARANKIN.
